HOLDER FOR NAPKINS AND CONDIMENT CONTAINERS

Vladimir A. d'Arbeloff, Riverside, Conn., assignor to Huck Products Corporation, New York, N.Y.

Filed May 4, 1960, Ser. No. 60,450

Term of patent 7 years

(Cl. D44—24)

— Fig. 2

FIG. 1 is a side elevational view of a holder for napkins and condiment containers showing my new design; FIG. 2 is a top plan view thereof; and FIG. 3 is a perspective view thereof.

I claim:

The ornamental design for a holder for napkins and condiment containers, as shown.
